(57) **CLAIM**

The ornamental design for a bag cartridge, as shown and described.

DESCRIPTION

FIG. 1 is a top perspective view of a bag cartridge showing my new design;

FIG. 2 is a bottom perspective view thereof;

FIG. 3 is a side elevation view thereof, all of the other side elevation views are identical;

FIG. 4 is a top plan view thereof;

FIG. 5 is a bottom plan view thereof;

FIG. 6 is a top perspective view of the bag cartridge of FIG. 1, with top portion removed to show aspects of the design that are not visible when combined;

FIG. 7 is a top view thereof; and,

FIG. 8 is a side elevation view thereof, all of the other side elevation views are identical.

The features shown in dashed lines form no part of the design and are not claimed.

1 Claim, 6 Drawing Sheets(56)
